UNITED STATES PATENT OFFICE

91,799

DESIGN FOR AN AUTOMOBILE

Fred B. Bergholt, Minneapolis, Minn.

Application April 5, 1933, Serial No. 47,699

Term of patent 14 years

To all whom it may concern:

Be it known that I, FRED B. BERGHOLT, a citizen of the United States, residing at Minneapolis, in the county of Hennepin, and State of Minnesota, have invented a new original, and ornamental Design for an Automobile, of which the following is a specification, reference being had to the accompanying drawing, forming part thereof.

In the drawing:

Figure 4 is a perspective view showing the design of the rear portion of the body with the bumper omitted.

I claim:

The ornamental design for an automobile, as shown and described.

Minneapolis, Minnesota, April 1, 1933.

FRED B. BERGHOLT.
